RADIO RECEIVING APPARATUS

Innokent N. Vorie, Tonawanda, N. Y., assignor to
 Colonial Radio Corporation, Buffalo, N. Y., a
 corporation of New York

Application August 13, 1937, Serial No. 158,844

11 Claims. (Cl. 250—20)

This invention relates to radio receiving apparatus and more particularly to improvements in radio receivers of the type disclosed in Matzner Reissue Patent No. 18,796, in which a flashing stop 5 signal is provided, showing when the tuning apparatus has arrived at the proper position to select any one or more of a number of chosen stations for which the receiver has previously been adjusted to give such a signal.

10 For the purpose of this description, such stations are herein termed "flash stations", because they may be selected by a flash signal of the receiver without reference to logs, newspaper guides, or the like, after having once been adjusted or keyed in the flash mechanism of the receiver.

The increasing power and crowding of transmitting stations in the ether channels, together with the increased amplification and selectivity 20 of receivers, making increased accuracy and exactness of tuning necessary, has introduced difficulties in the manufacture and operation of flash tuning receivers.

These recently arisen difficulties have been overcome to a very considerable degree by certain 25 inventions for which other patent applications have been or are being filed by the assignee of this application, in which there is disclosed a flash tuning receiver of the super-heterodyne type, in which the mechanism of the receiver may be 30 keyed or adjusted for flash tuning to a considerable number of stations, and which is mute, or substantially so, between flash tuning stations; that is to say, the receiver, when adjusted for 35 flash tuning operation, will respond only to flash tuning stations, and when being tuned from one flash tuning station to another, will not respond to intervening stations for which the mechanism has not been keyed, not to static, or power 40 line noises.

It is an object of this invention to provide a receiver of the type referred to, in which the muting system is considerably simplified.

It is a further object of this invention to provide 45 a receiver in which the muting system requires no relays for the operation of additional circuits, other than that closed by the flash mechanism of the dial itself.

It is a further object of this invention to provide 50 a receiver in which the closure of the dial control contacts for indicating a flash station in themselves serve to "voice" the receiver, without requiring the operation of supplemental contacts to operate or modify other circuits.

55 It is a further object of this invention to pro-

vide a receiver in which the receiver is controlled from the mute state, between flash tuning stations, to the "voiced" state, when tuned to a flash station, without the operation of any contacts other than the dial control contacts which serve to give the flash signal that the receiver is tuned to a flash station. 5

It is still a further object of this invention to provide muting mechanism for flash tuning receivers, which shall be more economical to manufacture and install than the previously known systems, without sacrificing operating efficiency in any respect. 10

A further object of this invention is to provide a pair of lamps, one of which be illuminated only 15 when a desired station is tuned in, while the other is lighted whenever the receiver is in use but not tuned to a desired station.

Still other objects and advantages of my invention will be apparent from the specification. 20

The features of novelty which I believe to be characteristic of my invention are set forth with particularity in the appended claims. My invention itself, however, both as to its fundamental principles and as to its particular embodiments, 25 will best be understood by reference to the specification and accompanying drawings, in which:

Fig. 1 is a schematic or block diagram of a receiver in accordance with my invention, and 30

Fig. 2 is a detailed circuit diagram of the improved muting system in accordance with my invention, showing so much of the circuits of the radio receiver as are necessary to an understanding of my invention. 35

My invention is disclosed herein, by way of example, as embodied in a super-heterodyne receiver arranged to operate from a commercial source of alternating current. It will be understood, however, that this by way of example, as certain of the principles of my invention may be applied to battery operated receivers, as well as those not involving the super-heterodyne principle. 40

My invention is illustrated applied to a receiver having a signal selector dial of the clock type in which a pointer moves over a dial, all of 45 which is exposed to view, with means for mounting tabs showing the call letters of the various stations, and a travelling flash signal light mounted in position to selectively illuminate any one only of the call letter tabs at a time; which receiver is provided with means for controlling the oscillator frequency to provide for exact and precise tuning of the desired signal over a considerably greater dial setting than would otherwise be possible, and in accordance with my in- 50 55

vention has simple and improved means for preventing or reducing any response of the loud speaker except when the receiver is tuned to a flash station (herein called "muting").

5 Referring now more particularly to Fig. 1, 1 designates any suitable form of antenna from which a signal voltage is drawn, and which may be amplified at its own frequency in amplifier 2 if desired, and with which there may be associated 10 selecting circuits of any desired type. After the desired amount of amplification, the signals are fed to a mixer or first detector tube 3 and mixed there with beat or heterodyne currents from oscillator 9, and from which they emerge at a lower frequency (so-called beat or intermediate frequency) and are then amplified by amplifier 4 to the desired extent at the beat frequency.

These further amplified signals are then applied to a discriminator and detector network 5. 20 At this point, it suffices to note that the discriminator and detector network has a pair of output circuits, to one pair of which it supplies audio frequency or voice currents derived from a second detection or demodulation of the signal, 25 and to the other of which it supplies a direct current voltage, herein termed oscillator frequency control voltage E_d , the magnitude of which is proportional, within limits, to the deviation of the intermediate or beat frequency being received, 30 from the calculated or design value, and the sign of which corresponds to the direction of such deviation. Since the said network is not, per se, a part of my invention, it is not herein described in detail.

35 This oscillator control voltage is applied to an oscillator frequency control circuit, operating in a manner to cause a change of the oscillator frequency in the direction required for correction of mistuning or drift in the receiver by an amount 40 such as to keep the intermediate frequency always at or very near the predetermined value for any particular station.

The audio frequency output of the detector and discriminator network is supplied to a suitable 45 audio frequency amplifier which may comprise tubes 6 and 7, and, after amplification to the extent desired, to a suitable signal indicator such as a loud speaker.

For flash tuning, the dial 11 may be constructed 50 to selectively receive a plurality of tabs 11a, 11b, 11c, etc., at various positions on the dial at which flash stations are received, as indicated by the pointer 12, and each tab carries the call letters of the particular station received at that dial 55 setting.

In addition, the flash control apparatus may be in the form of a dummy dial or "comb" 13, and a dummy pointer 14 carrying a spring finger 14a, relatively movable with respect to each other 60 and synchronized with the dial and pointer, and with the flash light arm 16a upon which apparatus the user may set up the adjustments to operate the flash signal at any desired dial settings.

65 Carried by the dummy dial or "comb" there may be provided a number of adjustable contact fingers 13a, 13b, 13c, etc., arranged when adjusted to make contact with spring finger 14a carried by the dummy pointer 14 and thus to 70 close a circuit between the comb and the spring finger at a number of predetermined dial positions. The position of the various fingers 13a, b, c, etc., is selected to correspond to the dial settings at which various selected flash stations 75 are received, so that a circuit is closed between

the dummy dial 13 and spring finger 14a at each position of the dial at which a flash station is received, there being one such position only for each flash station, and the position of each flash station being different from that of other flash stations, as will be understood.

When the circuit between comb and finger is closed at the position corresponding to that of a flash station, a circuit is operated including the flash indicator, which may be a lamp 16, mounted upon an arm 16a whose movements may be synchronized with those of the pointer 12 and which may be shielded so as to illuminate only the particular tab bearing the call letters of the flash station, which is received at that point.

10 Preferably, the apparatus is constructed in ways which will be described in more detail hereafter, so that the receiver is mute, when adjusted for flash tuning, except when the signal selector or tuning mechanism encounters a flash tuning station. When the circuit is closed between comb and spring finger, the flash indicator lamp 16 is energized, and the receiver circuits give "voice" to the receiver, so that when a tab is 20 illuminated to show a particular flash station being received, the loud speaker will reproduce the program of that particular station.

25 While the receiver is in a transition stage, being tuned away from one flash station to another, little or no response will be received from other stations, or from static or noise, between the flash station positions. When the position for another flash station is reached, the flash indicator will light, and the receiver will be "voiced". The circuits by which this is accomplished form particularly the subject of my invention.

30 Referring now more particularly to Fig. 2, 20 represents any suitable source of alternating current, which may for example be the house supply, in case the receiver is of the plug-in type 40 arranged to operate from a house source of alternating current. It may, however, be any other suitable source of alternating current for operating a radio receiver, such as a buzzer converter used for automobile receivers, or other apparatus.

35 The alternating current is preferably fed to a transformer 21 having primary and secondary windings 21a and 21b. From the secondary 21b, one side of which is preferably grounded, a conductor leads to flash signal lamp 16, which may travel around the dial 11 in synchronism with the pointer 12, as described, and is preferably located behind the dial in a manner to illuminate each tab when the station represented by the particular tab is received.

40 Lamp 16 is connected to spring finger 14a, and to one terminal of the primary 22a of a transformer 22, the other terminal of which may be grounded. Comb 13 may likewise be grounded. Lamp 33, if used, may be connected in shunt with 50 winding 22a.

45 The secondary 22b of said transformer may have a considerably larger number of turns than its primary, in order to step up the voltage output of said transformer. The output of said 55 transformer may then be rectified, as for example, by cathode 6a and diode anode 6b of tube 6, and the rectified voltage applied as a muting bias to the radio frequency, intermediate frequency, and audio frequency amplifier tubes of 70 the receiver.

55 Included in the circuit with secondary 22b and tube 6 is provided resistance 26 shunted by condenser 27 across which the rectified current builds up a voltage.

- The rectification herein shown as performed by tube 6 may be performed by any desired type tube which will rectify alternating current, such as a diode provided for the particular purpose.
- 5 However, it may equally well be, and preferably will be, one of the tubes provided for other purposes in the receiver, if it has a diode anode electrode not otherwise used.
- 10 By way of example, I have shown it as a tube of the type known in the art as a duplex-diode-triode which is employed in the receiver in this instance as an audio frequency amplifier. This tube may comprise cathode 6a, diode anodes 6b and 6c, control electrode 6d and anode 6e.
- 15 If diode anode 6b is not being used for any other purpose, it may be employed as the rectifier anode for the purpose of this invention, without interfering with the operation of the remaining electrodes of the tube for their own purposes.
- 20 The rectified voltage may be supplied through resistances 28 and 29 to the various grids of the tube to be over-biased for muting operation, which may be the radio frequency, the intermediate frequency, and the audio frequency amplifier tubes or either or all of them. By-pass condenser 27 may be provided across resistance 26 to insure that all, or substantially all alternating currents are removed before the voltage is applied as a bias voltage. For example, the muting over-
- 25 bias voltage may be applied through resistance 28 to the control grid 7c of audio frequency amplifier tube 7 and to the suppressor grid 2d of the radio frequency amplifier tube 2, and through resistances 29 and 30 to the control grid 6d of the audio frequency amplifier tube 6, and through resistance 29 to the suppressor grid 4d of the intermediate frequency amplifier tube 4. It will be noted that the connection supplying the over-bias to suppressor grids 2d and 4d is in place of the customary connection of the suppressor grid to the cathode of the same tube.
- 30 The operation of the system is as follows: when the receiver is turned on, and is in an intermediate position, no receiving a flash station, current is drawn by transformer primary 21a and supplied to the secondary 21b. The secondary current flows through the filament of flash signal lamp 16, and through the primary 22a to ground. The impedance of transformer primary 22a is so related to the remaining impedance of the circuit that most of the voltage drop occurs in the said transformer primary, and the filament of lamp 16 is not illuminated and the voltage drop across winding 22a keeps lamp 33 lighted. Lamp 35 16 will preferably be a low voltage, or heavy current lamp, while 33 is higher voltage or lower current lamp.
- 35 Under such conditions, secondary 22b draws current, and the turns ratio of this transformer is chosen to supply to its associated rectifier a sufficient voltage, which when rectified and applied to the control grids of the tubes to be muted, will over-bias them to the point of substantially no response.
- 40 When a flash station is tuned in, as will be seen, contact is made between spring finger 14a and one of the projections from comb 13, to ground, short-circuiting secondary 22b and lamp 33. This increases the voltage across the filament of lamp 16, so that it is then lighted and 33 extinguished. At the same time, current ceases to flow through secondary 22b and no current is rectified by tube 6, and hence there is no voltage developed across resistance 26, and the tubes to which an over-bias was previously applied for muting pur-
- 45 poses no longer receive such over-bias, but take their normal operating potential and operate in the normal way to amplify the voltage supplied to them.
- 50 When the station selector is operated to tune out the flash station to which the receiver was responding, contact between the comb 13 and spring finger 14a is interrupted, primary 22a again draws current, and the system operates to supply an over-biasing voltage to the muted tubes 10 as already described.
- 55 While I have shown and described certain preferred embodiments of my invention, it will be understood that modifications and changes may be made without departing from the spirit and scope of my invention, as will be clear to those skilled in the art.
- 60 I claim:
1. In a flash tuning radio receiver, in combination, a source of alternating current, an indicating lamp in series therewith, a relatively high impedance path in series therewith, a rectifier associated with said high impedance path, means for applying the output of said rectifier to at least one tube of said receiver as a muting bias, and means for completing the circuit of said alternating current source through said lamp exclusive of said high impedance path. 20
2. In a flash tuning radio receiver, in combination, a source of alternating current, an indicator lamp in series therewith, and a relatively high impedance path in series therewith, a rectifier associated with said high impedance path, means for applying the output of said rectifier to at least one tube of said receiver as a muting bias, and means for completing the circuit of said alternating current source through said lamp exclusive of said high impedance path, 30 said means comprising stationary and movable contacts relatively movable in synchronism with the signal selector of said receiver. 35
3. In a flash tuning radio receiver a single contact control system comprising, in combination, an indicating lamp for indicating the adjustment of flash tuning stations, a source of alternating current for energizing said indicating lamp, and having a transformer primary and secondary associated therewith, a rectifier associated with said secondary and having its output applied to at least one tube of said receiver as a muting bias, 45 and a pair of contacts movable relatively to each other synchronously with the signal selector of said receiver for short-circuiting said transformer primary. 50
4. In a flash tuning receiver, a single contact control system comprising, in combination, an indicating lamp for indicating the dial adjustment of flash tuning stations, a source of alternating current for energizing said indicating lamp, a transformer having its primary in series 60 with said indicating lamp, and having a secondary associated therewith, a rectifier associated with said secondary and having its output applied to at least one tube of said receiver as a muting bias, a circuit for short-circuiting said transformer primary, said circuit comprising a movable contact synchronized with the signal selector, and a plurality of contacts to be made by said first contact at dial positions, at each of which one of a group of previously selected transmitting stations is received. 65
5. In a flash tuning radio receiver, in combination, a source of alternating current, a flash signal lamp in series therewith, a transformer having primary and secondary windings in series 70
- 75

with said source and said lamp, the impedance of said primary being sufficiently high to prevent illumination of said lamp when current is flowing through said transformer primary, a rectifier associated with the secondary of said transformer, means for applying the output of said rectifier to at least one tube of said receiver as a muting bias, and means operable synchronously with the signal selector for short-circuiting said transformer primary at tuning positions of flash stations.

6. In a flash tuning receiver of the super-heterodyne type, comprising at least one radio frequency amplifier tube, in combination, a source of alternating current, an indicating lamp in series therewith, a relatively high impedance path in series therewith, a rectifier associated with said high impedance path, means for applying the output of said rectifier to said radio frequency amplifier tube as a muting bias, and means for completing the circuit of said alternating current source through said lamp exclusive of said high impedance path, said means comprising stationary and movable contacts relatively movable in synchronism with the signal selector of said receiver.

7. In a flash tuning receiver of the super-heterodyne type, comprising at least one radio frequency amplifier tube having a suppressor grid, in combination, a source of alternating current, an indicating lamp in series therewith, a relatively high impedance path in series therewith, a rectifier associated with said high impedance path, means for applying a direct current voltage from the output of said rectifier to the suppressor grid of said radio frequency amplifier tube as a muting bias, and means for completing the circuit of said alternating current source through said lamp exclusive of said high impedance path, said means comprising stationary and movable contacts relatively movable in synchronism with the signal selector of said receiver.

8. In a flash tuning receiver of the super-heterodyne type, comprising at least one intermediate frequency amplifier tube, in combination, a source of alternating current, an indicating lamp in series therewith, a relatively high impedance path in series therewith, a rectifier associated with said high impedance path, means for applying a direct current voltage from the output of said rectifier to said intermediate frequency amplifier tube as a muting bias, and means for completing the circuit of said alternating current source through said lamp exclusive of said high impedance path, said means comprising stationary and movable contacts relatively movable in synchronism with the signal selector of said receiver.
